UNITED STATES PATENT OFFICE

JOSEPH KNEIER, OF CLEVELAND, OHIO, ASSIGNOR TO THE VLCHEK TOOL COMPANY,
OF CLEVELAND, OHIO, A CORPORATION OF OHIO

SOCKET-WRENCH SET

Application filed December 17, 1927. Serial No. 240,702.

My invention relates to socket wrench sets, and the principal object of my invention is to provide a socket wrench set assembled in a manner convenient for merchandising. In the drawings accompanying this specification and forming a part of this application I have shown, for purposes of illustration, one form which my invention may assume, and in these drawings:

- 10 Figure 1 is a bottom plan view of the embodiment of my invention herein shown,
Figure 2 is a side elevation thereof,
Figure 3 is a view taken from one end, while
Figure 4 is a view taken from the other end.
15 In the embodiment of my invention herein shown I have assembled six sockets 11 each provided with an aperture 12 extending entirely through the socket 11 and terminating at one side in a handle-receiving recess 13 and at the other side in a nut-receiving recess 14, the nut-receiving recesses 14 varying in size over the six sockets 11 to form a regular progression from a smallest recess 14 in the smallest socket 11 adapted to receive a relatively smallest nut to a largest recess 14 in a largest socket 11 adapted to receive a relatively largest nut, and the handle receiving recesses 13 all being alike and adapted to receive either the end 15 of the long arm 16 of an 25 L-shaped handle 17 or the end 18 of the short arm 19 of this L-shaped handle 17, each of the ends 15 and 18 of the handle 17 being provided with stops 20 to limit the insertion of the handle 17 into the socket 11, and with 30 spring pressed detents 21 tending to hold the handle 17 engaged with any socket 11 with which the handle 17 has been assembled.
35 After assembling these six sockets 11, and this handle 17, I unite them into a single unitary set by means of a stringer adapted to be passed through the apertures 12 of the sockets 11 to receive the sockets 11 on an intermediate portion of the stringer, and then to have its ends secured to the ends of the handle 17.
40 In the embodiment of my invention herein shown I employ a stringer 22 formed from a single piece of wire 23 beginning at a loop 24 adapted to encircle the end 15 of the long arm 16 of the handle 17, extending from the loop 24 a short distance in the plane of the

loop 24 to form a short arm 25, then bent at right angles to the plane of the loop 24 to form a long arm 26 extending along the long arm 16 of the handle 17, adapted to be passed through the apertures 12 of the sockets 11 and to receive the sockets 11 thereon, and finally terminating in jaws 27 adapted to embrace the end 18 of the short arm 19 of the handle 17, the arms 25 and 26 of the stringer 22 being so proportioned relative to the arms 16 and 19 of the handle 17 that when the set is assembled the loop 24 encircles the end 15 of the long arm 16 of the handle 17 between the detent 21 of the end 15 and the stops 20 of the end 15 and the jaws 27 grip the end 18 of the short arm 19 of the handle 17 at a point inwardly of the stops 20 on the end 18.

Of course it will be understood by those skilled in the art that the sockets 11 may be disassembled from the handle 17 and from the stringer 22 to permit use of any one socket 11 with either end 15 or 18 of the handle 17 merely by springing the jaws 27 over the stops 20 of the end 18 of the handle 17 to remove the jaws 27 from about the end 18 of the handle 17, slipping the loop 24 from the end 15 of the wrench 17, and then removing the various sockets 11 from the stringer 22 over the jaws 27 by springing the jaws 27 in the reverse direction. Also it will be appreciated by those skilled in the art that normally, and until this intentional disassembly occurs, the stringer 22 will hold the sockets 11 assembled with the handle 17, that the single stringer 22 thus unites the six sockets 11 and the handle 17 into a single unitary package obviously well adapted for merchandising.

Under these circumstances it will be clear that the embodiment of my invention herein shown and described accomplishes at least the principal object of my invention, yet at the same time it also will be understood by those skilled in the art that this embodiment of my invention herein shown and described embodies advantages other than those specifically pointed out or suggested herein, and also that this particular embodiment of my invention may be variously changed and modified without departing from the spirit of my invention, or sacrificing the advantages there-

of, wherefore it will be understood that disclosure herein is illustrative only, and that my invention is not limited thereto.

I claim:

- 5 1. A socket wrench set holder, for holding a set of sockets each having an aperture extending therethrough and terminating at one side in a handle-receiving recess and at the other side in a nut-receiving recess, said handle-receiving recesses all being adapted to receive the same handle, said holder comprising: a handle, formed at at least one end to be inserted into any one of said handle-receiving recesses; and a stringer, adapted to 10 be passed through said apertures of said sockets to receive said sockets on a portion of said stringer, and formed on each side of said portion to be secured to said handle.
- 15 2. A socket wrench set holder, for holding a set of sockets each having an aperture extending therethrough and terminating at one side in a handle-receiving recess and at the other side in a nut-receiving recess, said handle-receiving recesses all being adapted to receive the same handle, said holder comprising: a handle, formed at at least one end to be inserted into any one of said handle-receiving recesses; and a stringer, adapted to 20 be passed through said apertures of said sockets to receive said sockets on a portion of said stringer, and formed on each side of said portion to grip said handle.
- 25 3. A socket wrench set holder, for holding a set of sockets each having an aperture extending therethrough and terminating at one side in a handle-receiving recess and at the other side in a nut-receiving recess, said handle-receiving recesses all being adapted to receive the same handle, said holder, comprising: a handle, formed at at least one end to be inserted into any one of said handle-receiving recesses; and a stringer, adapted to 30 be passed through said apertures of said sockets to receive said sockets on a portion of said stringer, and formed on each side of said portion to grip said handle.
- 35 4. A socket wrench set holder, for holding a set of sockets each having an aperture extending therethrough and terminating at one side in a handle-receiving recess and at the other side in a nut-receiving recess, said handle-receiving recesses all being adapted to receive the same handle, said holder, comprising: a handle, formed at at least one end to be inserted into any one of said handle-receiving recesses; and a stringer, adapted to 40 be passed through said apertures of said sockets to receive said sockets on a portion of said stringer, and formed on each side of said portion to grip said handle, on one side by encircling said handle, and on the other side by engaging said handle between resilient jaws.
- 45 5. A socket wrench set holder, for holding a set of sockets each having an aperture extending therethrough and terminating at one side in a handle-receiving recess and at the other side in a nut-receiving recess, said handle-receiving recesses all being adapted to receive the same handle, said holder comprising: an L-shaped handle, formed at at least one end to be inserted into any one of said handle-receiving recesses; and an L-shaped stringer, adapted to 50 be passed through said apertures of said sockets to receive said sockets on a portion of one arm of said stringer, and formed on said one arm beyond said portion, and also on the other arm, to grip said handle.
- 55 6. A socket wrench set holder, for holding a set of sockets each having an aperture extending therethrough and terminating at one side in a handle-receiving recess and at the other side in a nut-receiving recess, said handle-receiving recesses all being adapted to receive the same handle, said holder comprising: an L-shaped handle, formed at at least one end to be inserted into any one of said handle-receiving recesses; and an L-shaped stringer, adapted to 60 be passed through said apertures of said sockets to receive said sockets on a portion of one arm of said stringer, and formed on said one arm beyond said portion, and also on the other arm, to grip said handle, on said one arm by engaging one arm of said handle between resilient jaws, and on said other arm by encircling the other arm of said handle.

70 7. A socket wrench set holder, for holding a set of sockets each having an aperture extending therethrough and terminating at one side in a handle-receiving recess and at the other side in a nut-receiving recess, said handle-receiving recesses all being adapted to receive the same handle, said holder comprising: an L-shaped handle, formed at at least one end to be inserted into any one of said handle-receiving recesses; and an L-shaped stringer, adapted to 75 be passed through said apertures of said sockets to receive said sockets on a portion of one arm of said stringer, and formed on said one arm beyond said portion, and also on the other arm, to grip said handle.

80 8. A socket wrench set holder, for holding a set of sockets each having an aperture extending therethrough and terminating at one side in a handle-receiving recess and at the other side in a nut-receiving recess, said handle-receiving recesses all being adapted to receive the same handle, said holder comprising: an L-shaped handle, formed at at least one end to be inserted into any one of said handle-receiving recesses; and an L-shaped stringer, adapted to 85 be passed through said apertures of said sockets to receive said sockets on a portion of one arm of said stringer, and formed on said one arm beyond said portion, and also on the other arm, to grip said handle, on said one arm by engaging one arm of said handle between resilient jaws, and on said other arm by encircling the other arm of said handle.

90 9. In testimony whereof I hereunto affix my signature.

JOSEPH KNEIER.
